 Liberty Can and Sign Company, Lancaster,
 Pa., a corporation of Pennsylvania

Application May 15, 1935, Serial No. 21,653

10 Claims. (Cl. 220—41)

This invention relates to metal boxes of the resilient sheet metal sliding cover type such as now in extensive use for medicinal tablets and other small articles. In such boxes it is now usual to provide stop means for limiting the relative sliding movement between the cover and body in one or both directions.

Most such stop means are simply somewhat rounded lugs struck up from, or down into, the body or sliding top at some distance, relatively speaking, inward from the side of the body or top and in operation theoretically abut against the rounded edge of the end of the top of the body, or against a flange of the top, in a line 15 lying inward of the side of the box for an appreciable distance as stated. In actual practice it is found that because of their rounded or wedge form and their location when but very slight excess pressure is exerted the metal of the top 20 or body or both, because of its resilient yielding character, springs and yields with the result such stops ride over and past the abutment or, in other words, the stops fail to function in practice.

The primary objects of the present invention are to provide a resilient sheet metal box of the above type wherein the body is formed with a top edge curl and the top is formed with downwardly and inwardly curved side flanges snugly fitting about and under the body curl, the construction of said parts and the resilient nature of the material from which they are formed serving to hold the lower portions of said flanges drawn up tightly against the opposing lower laterally outer face portions of said curl and said flanges serving to hold the laterally outer portions of said top in tight sliding contact with the upper face portion of said curl and to so form said top and curl in the plane of said curl in a direction parallel to the adjacent side of the body and substantially perpendicular to the general plane of the top with interengaging stop means, whereby said stop means will at all times 45 be held in operative relationship by the engagement of the flange with the curl and cannot be forced past each other without the use of such force as to permanently stretch or deform and so destroy the box; to provide such a box with 50 positive stop means while avoiding any unprotected sharp corners or edges that would be apt to scratch or mar the lithographed or other finish of adjacent box parts as the same issue from the forming machines and drop into receiving baskets or receptacles; and to effect economy in

the use of material and simplify the stamping and assembly operations.

In the accompanying drawing:

Figure 1 represents a top plan view of my invention, according to the preferred embodiment, closed;

Figure 2, a top plan view of the body thereof;

Figure 3, a side elevation of the box, open;

Figure 4, a cross-section on line 4—4 of Fig. 1, looking in the direction of the arrows, the cover being shown in its initial stage of application to the body;

Figure 5, a view similar to Fig. 4, the cover being in its intermediate stage of application to the body;

Figure 6, a view similar to Fig. 4, the cover being in its final stage of application to the body;

Figure 7, a sectional view on the line 7—7 of Fig. 1, looking in the direction of the arrows;

Figure 8, a view, similar to Fig. 7, of a modified form; and

Figures 9 and 10 respectively side elevation and fragmentary top plan views of a further modification.

In all of the views the thickness of the sheet metal employed has been greatly exaggerated, and in general the parts have been enlarged and made somewhat out of proportion in order to clearly show the invention on a sufficiently large scale and without requiring a multiplicity of sheets of drawings.

Referring now in detail to the drawing, A designates the body of the box; B, the sliding top; D, lugs or ribs struck or pressed out laterally from the sides of the body to overlie the edges of an opening in a display card if desired; E, the usual snap catch lug or latch stamped down or inward in the top B to engage and ride up over the end edge curl as the top B is shoved toward closed position and, as soon as the top 40 B reaches closed position, snapping down by the resiliency of the top B and fitting inside of, and engaging the adjacent end face of, the body A to hold the top B closed against accidental or unintentional displacement; and F, a hook type 45 or form end stop formed on the end of top B adjacent catch E to engage the end of body A or the adjacent portion of the end edge curl thereof to prevent sliding movement of the top B in the direction of closing beyond closed position.

As illustrated in Figures 1 to 7 inclusive, in the present preferred form, the body A has its edge portion rolled or curled into a preferably continuous external bead or curl 1 of preferably substan-

tially uniform diameter in cross-section. Preferably midway of the length of each side of the body said curl is abruptly struck up to form two abrupt lugs 3 preferably substantially in transverse registry in a plane parallel to the end of the body and each extending vertically upward and for a short distance lengthwise of the box in a vertical plane substantially parallel to, and laterally outside of, the vertical plane of the corresponding side of the body A.

The sliding top or cover B will preferably be slightly arched in form with an outwardly and downwardly inclined marginal panel 6 extending completely around it and will preferably be springy or resilient as a whole preferably cross-wise and as applied to the body A the top B will preferably be under tension cross-wise and preferably also lengthwise, particularly when it is closed. The sides of the top B are formed with preferably integral downwardly and inwardly curved flanges 2 to snugly fit about and below, and slidably receive, the side portions of the curl 1 of the body A, which is of resilient construction, or preferably of such material and construction as to be resilient as a whole. The top B is formed with two longitudinal upwardly pressed grooves 4 so located as to respectively lie in the respective longitudinally extending vertical planes of the respective stop lugs 3 in the respective planes of the respective side portions of the bead or curl 1 and thus being at the extreme side portions of the top B and lying substantially in the same planes as, or laterally outside of, the sides of the body A, the curved ends of each groove 4 constituting stop shoulders or faces 5 adapted to abut the opposed faces of the corresponding stop lugs 3 to limit the movement of the top B with respect to body A, and being prevented from riding up over said stop lugs 3 by reason of the fact that the camming or wedging action would be practically in a straight vertical line in a vertical plane intersecting the groove 4, the lug 3 and the side portion of the curl 1, approximately intersecting or being coincident with the axis of said side portion of the curl 1 in each instance, so that in each instance it would involve a straight pull or shove between the shoulders 5 and the lugs 3 respectively in opposition to the engagement of the lower portions of the flanges 2 with the lower outer faces of the respective side portions of the curl 1, all such points of engagement in each instance, or as to each side of the top B, taking place substantially in the same longitudinally extending vertical plane, so that in order for one pair of shoulders 5 to be forced up over and beyond the stop lugs 3 it would be necessary to intentionally and deliberately use sufficient force to definitely stretch or tear and permanently deform and destroy the box.

In assembling, the top B and bottom A constructed as above described are initially associated with the flange 2 on one side of the top B hooked under the corresponding side portion of the curl 1 of the body A and with the flange 2 on the other side of the top B resting on the stop lug 3 on the other side of the body A, as illustrated in Fig. 4. Next, pressure is applied to press, deform temporarily or temporarily spring inward the latter side of the body A and at the same time move the latter flange 2 down along the outer side of said stop lug 3, as shown in Fig. 5, and thereafter this side of the top B and body A are pressed or squeezed together until the outer portion of panel 6 on that side of the top B rests on the top of that side portion of curl 1 and the corresponding flange 2

fits down around and under said portion of the curl 1, the resilient springy construction of the body A, or of top B, or of both top B and body A serving to hold the top B spread under tension, forcing the inner faces of the lower portions of the flanges 2 into contact with the lower portions of the outer faces of the respective side portions of the curl 1 and at the same time through such engagement holding the outer portions of the side panels 6 in engagement with the upper faces of 10 said side portions of the curl 1.

In the modification illustrated in Figure 8 the construction and operation are the same as above described with relation to the preferred form, except that instead of the curl 1 being formed with 15 upwardly struck lugs 1 it is formed with a downwardly pressed section on each side portion, said depressed section 3' terminating in stop shoulders 5' and functioning the same as the groove 4 and stop shoulders 5 of the preferred form, and the 20 top is formed with a downwardly or inwardly pressed stop lug 4' having movement lengthwise of said depressed portion or section 3' on each side and abutting the stop shoulders 5' to limit the reverse endwise movement of the top. 25

In the modification illustrated in Figures 9 and 10 the construction and operation are the same as in the preferred form except that instead of the grooves 4 the metal of the top is cut out in the form of slots 4a respectively having the form 30 and location of the grooves 4 of the preferred form, and the end edges 5a of said slots 4a constitute stop shoulders functioning the same as the stop shoulders 5 of the preferred form, though probably with somewhat greater efficiency in that 35 they have raw cutting edges that would tend to bite into the opposed end faces of the stop lugs 3 instead of having a tendency to slide thereon.

I claim:

1. A sheet metal slide cover type box comprising 40 a rectangular body formed with an external top edge curl, a lug projecting from each side portion of said curl extending longitudinally and vertically in a vertical plane parallel to its adjacent side of said body with its major portion disposed laterally 45 outside of the vertical plane of said side of said body and with its laterally outer face in the same vertical plane as the extreme laterally outer face portion of its corresponding side portion of said curl, in combination with a rectangular sliding 50 resilient sheet metal cover arched both lengthwise and crosswise, side flanges integral with said cover and curved downwardly and inwardly to snugly slidingly engage about and under the outer and lower faces of the respective side portions of said curl, said top being formed with upwardly indented longitudinally extending grooves respectively located in its respective extreme laterally outer portions and so disposed as to slidingly receive the respective stop lugs, and abutment faces 55 formed at the ends of each said groove.

2. A sheet metal slide cover type box comprising a rectangular body formed with an external top edge curl, a lug projecting from each side portion of said curl extending longitudinally 65 and vertically in a vertical plane parallel to its adjacent side of said body with its major portion disposed laterally outside of the vertical plane of said side of said body and with its laterally outer face in the same vertical plane as the extreme 70 laterally outer face portion of its corresponding side portion of said curl, in combination with a rectangular sliding resilient sheet metal cover arched crosswise, side flanges integral with said cover and curved downwardly and inwardly to 75

5 snugly slidably engage about and under the outer and lower faces of the respective side portions of said curl, said top being formed in its extreme laterally outer portions with longitudinally extending slots so located and respectively of such width as to snugly slidably receive said stop lugs respectively, the end walls of said slots respectively constituting thin abrupt abutment shoulders.

10 3. A sheet metal slide cover type box comprising a rectangular body formed with an external top edge curl, the side portions of said curl between the ends of said body being depressed to form a clearance depression on each side of said body, the end walls of said depressions respectively constituting abutment shoulders lying in the vertical planes of the respective side portions of said curl in combination with a rectangular sliding resilient sheet metal cover arched crosswise, side flanges integral with said cover and curved downwardly and inwardly to snugly slidably engage about and under the outer and lower faces of the respective side portions of said curl, and stop lugs depending respectively from the extreme 15 laterally outer portions of said cover in vertical registry respectively with the respective depressed portions of said respective side portions of the curl and adapted to have movement lengthwise thereof and to engage the respective abutment shoulders constituting the end walls thereof.

20 4. A sheet metal slide cover type box comprising a body formed with an external top edge curl, portions of said curl carrying short abrupt stop lugs extending in a vertical plane intersecting the center of the corresponding portion of said curl, in combination with a sliding resilient sheet metal cover, flanges integral with said cover and curved downwardly and inwardly to snugly slidably engage about and under the outer and lower faces 25 of the respective corresponding portions of said curl, said cover being formed with upwardly indented longitudinally extending grooves respectively located in its respective extreme outer portions and so disposed as to slidably receive the respective stop lugs, and abutment faces formed 30 at the ends of each said groove.

45 5. A sheet metal slide cover type box comprising a body formed with an external top edge curl, and short abrupt stop lugs respectively extending vertically from the top faces of the respective side portions of said curl between the ends of said body, in combination with a sliding resilient sheet metal cover arched crosswise, side flanges integral with said cover and curved downwardly and inwardly to snugly slidably receive and engage about and under the outer faces of the respective side portions of said curl, said top being formed in its extreme laterally outer portions with longitudinally extending slots so located and respectively of such width as to snugly slidably receive said stop lugs respectively, the end walls of said slots respectively being adapted to engage said stop lugs to limit the endwise movement of said cover relative to said body.

60 6. A sheet metal slide cover type box comprising a rectangular body formed with an external top edge curl, and abrupt stop lugs respectively extending vertically from the top faces of the respective side portions of said curl between the ends of said body, in combination with a rec-

5 tangular sliding sheet metal cover, side flanges integral with said cover and curved downwardly and inwardly to snugly slidably engage about and under the outer and lower faces of the respective side portions of said curl, said cover being formed with longitudinally extending sockets respectively located in its respective extreme laterally outer portions and so disposed as to slidably receive the respective stop lugs, and abutment faces at the ends of said sockets.

10 7. A metal slide cover type box comprising a body formed with an external top edge curl, and a stop lug extending vertically from the top of said curl, in combination with a sliding metal cover, flanges integral with said cover and curved 15 downwardly and inwardly to snugly slidably engage about and under the outer faces of the respective corresponding portions of said curl, said cover being formed in an extreme outer portion with a slot so located and of such width as to 20 snugly slidably receive said stop lug, and abutment faces formed at the ends of said slot to respectively abut the stop lug to limit the movement of said cover relative to said body.

25 8. A metal slide cover type box comprising a body formed with an external top edge curl, and an abrupt stop lug extending from the top of said curl, in combination with a sliding metal cover, flanges integral with said cover and curved downwardly and inwardly to snugly slidably engage about and under the outer faces of the respective corresponding portions of said curl, said cover being formed with a socket in an extreme outer portion and so disposed as to slidably receive said stop lug, and abutment faces formed 30 at the ends of said socket to respectively abut the stop lug to limit the movement of said cover 35 relative to said body.

40 9. A sheet metal slide cover type box comprising a body and a sliding sheet metal cover, one 40 of said elements being resilient, and said body being formed with an external top edge curl, in combination with side flanges integral with said cover and curved downwardly and inwardly to snugly slidably engage about the outer faces 45 of the respective side portions of said curl and an extreme laterally outer portion of said cover and one of said side portions of said curl each being provided in the vertical plane of said curl portion with a pair of abrupt vertically extending faces located above the longitudinal center of said curl portion, one pair of said faces being interposed between the abutment faces of the other pair.

45 10. A metal slide cover type box comprising a 55 body formed with an external top edge bead, in combination with a sliding metal cover, side flanges integral with said cover and curved downwardly and inwardly to snugly slidably engage about the outer faces of the respective side portions of said bead, and an extreme laterally outer portion of said cover and one of the side portions of said bead each being provided above the longitudinal center, and in the vertical plane thereof, of said bead with a pair of abrupt vertically 60 extending abutment faces, one pair of said abutment faces being interposed between the abutment faces of the other pair.
